Primary Examiner—Cynthia E. Ramirez*(74) Attorney, Agent, or Firm*—Jeffrey D. Peterson; Michael Best & Friedrich LLP(57) **CLAIM**

The ornamental design for a ring lift anchor, as shown and described.

DESCRIPTION

FIG. 1 is a top plan view of the ring lift anchor showing my new design;

FIG. 2 is a front view thereof;

FIG. 3 is a side view thereof; and,

FIG. 4 is a perspective view thereof.

The present application is directed to the design illustrated in the drawings. The broken line portions of the disclosure are for illustrative purposes only and form no part of the claimed design.
